UNITED STATES PATENT OFFICE.

FRANK A. ADAMS, DECEASED, LATE OF ROCHESTER, NEW YORK; BY TERESA CATHERINE ADAMS, ADMINISTRATRIX, OF ROCHESTER, NEW YORK, ASSIGNOR, BY MESNE ASSIGNMENTS, TO WASH-ALL MACHINE CORPORATION, OF ROCHESTER, NEW YORK, A CORPORATION OF DELAWARE.

EXPANSIBLE-CHAMBER MOTOR.

Application filed March 3, 1923. Serial No. 622,609.

To all whom it may concern:

Be it known that FRANK A. ADAMS, deceased, late a citizen of the United States, and late a resident of Rochester, in the 5 county of Monroe and State of New York, did invent certain new and useful Improvements in Expansible-Chamber Motors; and the following is declared to be a full, clear, and exact description of the invention, such 10 as will enable others skilled in the art to which it appertains to make and use the same.

This invention relates to motors of the expansible chamber type particularly adapted 15 to be operated by water.

Its objects are to improve and simplify the construction of such motors, and to render their operation certain and relatively silent.

20 The invention comprises a combined motor support and valve casing, a cylinder and housing supported thereby, the essential operating parts therein, together with the sub-combinations and details of structure more 25 specifically set forth in the ensuing description, illustrated in the accompanying drawings and defined in the appended claims.

In the drawings in which like reference characters indicate like parts throughout the 30 several views:—

Figure 1 is a vertical section, taken longitudinally through the motor cylinder and main valve chamber, showing the piston at the upper end of its stroke and the valves 35 in position corresponding;

Fig. 2 is a similar section of the lower part of the motor cylinder and main valve chamber showing the position of piston and valves at the other end of the piston stroke;

40 Fig. 3 is a vertical section through the pilot valve chamber showing the pilot valve in position corresponding to the position of the main valve and piston in Fig. 2;

Fig. 4 is a vertical section similar to Fig. 3 45 but showing the pilot valve in the position which it occupies corresponding to the position of the main valve and piston illustrated in Fig. 1;

Fig. 5 is a top plan view of the combined 50 motor support and valve casing;

Fig. 6 is an end elevation of the parts

shown in Fig. 5 viewed from the right side thereof, a portion having been broken away to disclose the upper end of the pilot valve and a finger adapted to operate it; 55

Fig. 7 is a detail plan view of the finger by which the pilot valve is connected to the valve trip rod, and

Fig. 8 is a view partly in side elevation and partly in section of the lower end of 60 the motor.

Although the motor disclosed herein will operate in any position, this description assumes that the motor is mounted with the cylinder in an upright position, motor support and casing 1 being held to a horizontal plate, bracket or other suitable holding means by insertion of threaded part "a" 65 through an opening therein and clamping the holding means between the flange "b" 70 and a nut screwed on the threaded part "a."

In the drawings, numeral 1 indicates the combined motor support and valve casing as an entirety; 2 the motor cylinder; 3 the housing surrounding said cylinder; 4 a cap 75 secured to the housing and centrally perforated to serve as a guide for the piston rod; 5 the piston and 6 the piston rod sliding through the cap 4.

Said combined support and casing 1 comprises a cylindrically bored valve casing 7, 80 within which operates the main valve 8,—said casing 7 being disposed at right angles to the axis of the cylinder 2,—and a pilot valve casing 9 disposed at one side of the 85 casing 7 at right angles to the latter within which slides the pilot valve 10. In addition to the parts for incasing the main valve and pilot valve, an integral cylinder and housing supporting member 11 extends upward from 90 the main valve casing. In this supporting member 11 is an annular inner seat 12 to which the inner or lower end of the cylinder 2 is secured. Preferably the lower end 95 of cylinder 2 is exteriorly threaded and screwed into a correspondingly threaded opening in seat 12. On member 11 above the seat 12 is a larger seat 13 in registration with the seat 12 and having an axis lying in the same straight line as the axis of seat 12.

Within the seat 13 is secured the lower end 100 of the motor housing 3 and it, also, is prefer-

ably threaded to said seat as shown. The two seats 12 and 13 are separated in the direction of their axes, the seat 13 being some distance above the seat 12. Between them there is formed in the casing an annular chamber 14 which communicates by an annular port 15 with the elongated passage 16 between the outer surface of cylinder 2 and the inner surface of motor housing 3. The upper end of the motor housing 3 preferably extends above the upper end of the cylinder 2 as shown particularly in Fig. 1, thus providing for a clear unobstructed annular fluid duct between the chamber 14 in the part 11, of the combined support and casing, and the upper, open end of the cylinder 2. Both cylinder and housing are unsupported otherwise than by their connection to seats 12 and 13.

20 The cap 4 may be threaded or soldered to the upper end of the housing 3 said cap having an annular skirt or flange 17 which embraces the upper end of housing 3. The upper portion of said cap 4 is reduced as shown at 4^a and is centrally bored to permit the passage of the piston rod 6. Reduced portion 4^a is also counter-bored from the interior, or has otherwise formed therein a cylindrical cavity 18 adapted to accommodate packing for preventing leakage of pressure around the piston rod where it passes through said cap. Between the skirt 17 and the lower end of said bore 18 inwardly projecting supporting means such as lugs or a flange 19 are formed within the cap; resting upon said supporting means is a bridge 20 adapted to permit passage of piston rod 6. In the upper end of the bore 18 suitable packing material is confined. A suitable packing may consist of one or more washers 21 of rubber, fiber or the like supported by an unyielding washer 22, of metal. Between the lower face of said washer 22 and the upper surface of the bridge 20, a coiled compression spring 23 exerts its expansive pressure to keep the packing tight.

50 The lower part of piston rod 6 is hollow or bored as at 6^a for at least a distance equal to the length of its stroke for a purpose that will presently appear. The bore 6^a does not extend through the piston rod but said rod may be made of a tube plugged at a suitable distance from its lower end. Threaded to the lower end of piston rod 6, at 24, is a disk-like piston plate 25. A second piston plate 26 is sleeved over the piston rod 6 above plate 25. Piston plate 25 has holes to permit the passage of screws 27 and the piston plate 26 has threaded holes registering therewith to receive the threaded ends 28 of said screws. Between the plates 25 and 26 are clamped two pump leathers or cupped piston packings 29 disposed with their concave sides facing in opposite directions as is customary in piston packings of

this type. Secured to the lower face of the piston 5 by said screws 27 is a shifter-rod actuating-plate 30 which has a central opening of less diameter than the bore of the piston rod 6 and registering therewith.

Just below the threaded portion of the inner or cylinder receiving seat 12 in the casing 1 is formed a suitable ledge or equivalent rest 32. Upon the ledge 32 rests a plate or member 33. Said member 33 has a central opening in which the shifter rod 31 is guided and also has a plurality of passages 35 to let water pass freely from one side to the other. The upper end of shifter rod 31 has a head 36 of such diameter as to slide within the hollow piston rod 6 but to be prevented from passing out from the lower end of the bore of the piston rod by engagement of the plate 30 with the under side of said head. The piston 5, therefore, when near the limit of the upward stroke will, by reason of the engagement of the head 36 and the plate 30, lift the shifter rod 31. Secured on the lower end of the rod 31 are two spaced-apart stop or limiting members, such as metallic plates 37 and 38, portion 39 of the shifter rod between them being guided in the central opening in said member 33. Above and backing the limiting member 37 is a rigid collar 40 having an upper shoulder 41 that is adapted to be engaged by the plate 30, or lower face of the piston 5, when the latter is near the limit of its downward stroke in order to shift said rod in the opposite or downward direction. At the lower end of said shifting rod is secured a pilot valve shifting finger 42 which, as shown, is offset slightly downward and extends to one side of the axis of the cylinder. The finger 42 is screwed as at 43, or secured in any suitable manner to the lower end of the shifter rod 31 and upon its upper face rests the limiting member 38.

In the illustrated embodiment the lower end of shifter rod 31 is screw threaded. Collar 40 is threaded on the threaded end of the rod, limiting member 37 secured over said rod and clamped between collar 40 and a threaded sleeve constituting the guide portion 39 referred to. Limiting member 38 is rigidly clamped between the lower end of sleeve 39 and the upper side of finger 42. The members 37 and 38 are circular plates of such diameter as to extend over the holes 35 in stop plate 33, and said plates are slightly dished or provided with central bosses 37^a and 38^a, which may be produced by a stamping operation, on the sides thereof that contact with the stop plate 33 at the limits of reciprocation of the shifter rod. These limiting plates constructed as described produce a partial throttling of the water at the ends of the motor strokes, acting to cushion or retard movement, reducing the shock and substantially eliminating the

noise produced by metal striking against metal, and avoid the need of soft packings, which have to be replaced from time to time.

The outer end of said finger 42 is notched 5 as indicated at 44 in Fig. 7, the notched end being adapted to engage in a groove 45 formed about the upper end or neck of the pilot valve 10, said groove being of a width much greater than the thickness of 10 finger 42 in order to provide lost motion to permit the limiting members 37 and 38 (and shift rod) to be pushed away from the guide and stop plate 33 by the incoming water or drop away by gravity, respectively, un- 15 hindered by the pilot valve. The neck of the pilot valve 10 projects into a chamber 46 which is in communication with the upper end of the pilot valve chamber in casing 9 and with the lower end of the cylinder 2; 20 the upper end of the pilot valve, therefore, is subjected to the pressure of water entering or leaving the lower end of cylinder 2. It will be apparent that as the piston recipro- 25 cates it will, as it approaches the upper end of its stroke, cause an endwise shift of the pilot valve 10 in an upward direction by means of the connection described and, as it approaches the lower end of its stroke, an endwise movement of the pilot valve in 30 downward direction.

The main valve casing 7, for convenience of manufacture, is bored completely through from end to end, the opposite ends of said bore having internal screw threads 47 for 35 the reception of correspondingly threaded plugs 48. Each of said plugs is provided with a flange 49 between which and the ends of the casing a suitable packing gasket 50 is disposed. In order that the plugs 48 may 40 be easily tightened or removed the flanges 49 are of polygonal contour as at 51, so that they may be engaged by a wrench. Centrally disposed within the inner end of each 45 plug is a buffer 52 adapted to cushion the impact of the main slide valve 8 when shifted to either limit of its stroke. Each buffer 52 is preferably of rubber secured in a central opening 53 in a tubular boss 54 the end of which is adapted to be swedged or 50 contracted upon the buffer to hold it securely in place, the end of said boss 54 ex- 55 tends not beyond the threaded part of the plug, and being separated therefrom by an annular channel.

Projecting from one side of the valve casing 7, as shown in Figs. 5 and 6, are hose nipples 55 and 56 communicating with ports disposed at opposite sides, as shown in this embodiment, of a vertical line coincident 55 with the axis of the cylinder. To said nipples rubber hose or other fluid conductors may be coupled. The port in communication with the nipple 55 may be considered as the inlet port for motive fluid and the 60 port communicating with the nipple 56 as

the exhaust port. Within the bored casing 7 there are a number of transverse annular enlargements, chambers, or grooves adapted to afford free passage of the motive water from the inlet to one end or the other of the cylinder and from one end or the other of the cylinder to the exhaust port in accordance with the position of said valve 8. The annular chamber 57 is in direct communication with the inlet port, which opens into 70 it. The annular chamber 58 is in direct communication with the chamber 46 through port 46^a and through chamber 46 with the lower end of the cylinder 2. The annular chamber 59 is in direct communication with the exhaust port which opens therefrom. The chamber 60 is in direct communication with the said annular chamber 14 in member 11 of the casing by means of a large duct or passageway 61 which connects said chambers and therefore conducts the motive fluid 75 to or from the upper end of the cylinder. 80

Valve 8 comprises an elongated body having cylindrical lands 63, 64, 65 and 66, nicely fitting the bore of the casing 7. The end lands 63 and 66 function as piston heads to enable the valve to be shifted in a manner to be presently explained. Between lands 63 and 64, lands 64 and 65, and lands 65 and 66 the valve body is reduced in size to 90 provide water passages around the valve body. Between the end lands or piston heads 63 and 66 the valve 8 is cored or hollow as indicated at 62. One end of the passage 62 thus formed opens through ports 100 62^a into the space between lands 63 and 64, the other end of said passage communicating through ports 67 and 68 with the space between lands 65 and 66. 105

When the valve 8 is in the position indicated in Fig. 1 the said inlet chamber 57 is in communication with the chamber 60 through the ports 67 and 68 passageway 62 and ports 62^a in the valve 8; and under the same conditions the said exhaust or outlet chamber 59 is in communication with the chamber 58 around the exterior of the valve 8 between lands 64 and 65. With the valve in the position shown in Fig. 1, therefore, water entering through the nipple 55 passes to chamber 57 and thence through the passageway 62 in the valve to the chamber 60 from which it flows through duct 61 to annular chamber 14, annular duct 16, into the upper end of the cylinder 2. At this time chamber 58 being in communication with the chamber 59 around the exterior of the valve 8 between lands 64 and 65 the exhaust water forced ahead of the piston 5 in its downward movement enters the chamber 58 and thence passes into chamber 59, and through the exhaust port into the nipple 56. In Fig. 1 the piston is shown at the upper end of its stroke, the pilot valve having 115 been shifted and having caused the move- 120

ment of the valve 8 to the right, as viewed in this figure, in a manner to be presently explained. At this time, in accordance with the mode of operation described, the piston 5 is about to start downward.

In Fig. 2 the piston 5 is shown as having reached the lower end of its stroke, the valve shifting rod 31 has been moved downward by engagement of the shoulder 41 with the lower face of the piston and the pilot valve 10 has been moved downward to the opposite end of its stroke and by means to be hereinafter described, has caused the valve 8 to be shifted to the left as shown in Fig. 2, the parts being now in position to reverse the stroke of the piston and move it upward. At this time, water entering the nipple 55 passes to chamber 57, thence around the barrel of the valve between the lands 65 and 66 and through ports and passageways 68, 62, 67 into chamber 58 whence the water can pass only upward into chamber 46, from which it passes through the openings in guide 33 to the lower end of the cylinder 2 applying pressure to the bottom of the piston 5. In this position, the passage 62 through the valve is closed at the left hand end by reason of the fact that lands 63 and 64 are at that time engaging the cylindrical wall of the chamber 7 at its left hand end and there is then no outlet for water between these lands. As the piston 5 rises it forces water before it from the upper end of the cylinder into the annular passage 16, annular chamber 14, passageway 61, to chamber 60. Chamber 60 is now in communication with chamber 59 around the barrel of the valve between lands 64 and 65 and the water therein can only escape by passing through the exhaust port into the nipple 56. The operations described are repeated in succession as long as the motor continues to operate.

Referring now to Fig. 4, the mode of operation of the pilot valve 10 will be described. In Fig. 4 said pilot valve is shown at the upper end of its stroke in the same position in which it is indicated in Fig. 1 and has caused a shifting of the slide valve 8 to the position shown in said Fig. 1. Comparing Fig. 4 with Fig. 1 it is to be remembered that in Fig. 4 the parts are viewed from the rear side of Fig. 1 and therefore appear in reverse position. The pilot valve casing 9 comprises a cylindrical chamber or bore 70 extending from the lower end thereof into the described chamber 46. The lower end of the chamber 70 is closed by a threaded plug 71 having a polygonal flange between the inner surface of which and the lower end of the casing 9 is clamped a suitable gasket 72. The length of the bore 70 and the vertical distance between the top wall of chamber 46 and inner end of plug 71, as compared with the length of the pilot

valve 10 and the amplitude of its stroke are such that in operation the ends of the pilot valve never strike the top wall of chamber 46 nor plug 71; limiting members 37 and 38 on pilot valve shifter rod 31, cooperating with guide and stop plate 33 insure this result. Cast with the casing 1, longitudinal of the main valve chamber, and connected at their inner ends with the casing 9, as shown in the present embodiment, are a plurality of ribs within which the several ducts providing the necessary communication between the main valve chamber and the pilot valve chamber are formed. It will be understood that these ribs afford the necessary material without adding unnecessary weight to the said casing but they are not essential to the structure. The ducts may consist of tubes or may be drilled in the wall of the casing if said wall is thick enough. The duct 73 is in communication at one end with the chamber 70 and at the other end through a transverse port or passage 74 with the chamber 57 which, in turn, it will be remembered, is in communication with the in't port. The duct 75, which is in communication with the bore 70 of casing 9, as shown in the present embodiment, on the opposite side thereof from its connection with the duct 73 and above it, extends longitudinally of and to one end of the main valve casing 7 where it communicates with a transverse port 76 which enters the main valve chamber at the left hand end thereof as viewed in Fig. 1. The duct 77, shown below the duct 73, communicates at one end with the bore 70 of pilot valve casing 9 and at the other end with a transverse port 78, which enters the chamber in the slide valve casing 7 at the extreme right hand end thereof (see Fig. 2). The duct 73 is for the purpose of admitting motive fluid into the bore of the pilot valve casing 9. The ducts 75 and 77 are for the purpose of transmitting motive fluid under pressure into the opposite ends of the valve chamber in casing 7 for the purpose of shifting the valve 8 to one end or the other of the chamber at the proper time. In addition to the said controlling ports and passageways there is a duct 79, shown disposed above the duct 75, said duct 79 being in communication with the bore 70 of pilot valve casing 9 and by its transverse port 80 with the annular chamber 59 in the casing 7 which, it will be remembered, is in direct communication with the exhaust port. The pilot valve 10 is a generally cylindrical body having lands 84, 85, 86 and 87, the valve body being reduced between said lands so as to provide annular passages for water. An elastically expansive piston ring 10^a is fitted in a circumferential groove in said valve 10 for the chief purpose of causing adequate friction between said valve 10 and the

and casing in order that the valve may not move except as it is forced to move by the finger 42 at the end of shifter rod 31, thus affording steadiness of operation and allowing the shifting rod to move freely initially and open wide the ports 35 in the plate 33 without interference from the pilot valve. Said pilot valve is bored as at 88, said bore having communication at its upper end between the lands 84 and 85 with the exterior of the valve through ports 89, and at its lower end by ports 90, with the exterior of the valve between the lands 86 and 87. The lower end of said valve 10 is closed as by plug 91.

With the main valve 8 in the position indicated in Fig. 1 and the pilot valve 10 in the position corresponding thereto, as indicated in Fig. 1 and Fig. 4, it will be recalled that motive water was being directed into the upper end of the cylinder and the piston was about to move downward. At this time water under pressure from the inlet chamber 57 has entered through port 74, leading from the latter duct 73, into the bore 70 of pilot valve chamber 9 between the lands 85 and 86, has crossed over into the duct 75, passed through port 76 into the chamber of valve casing 7 at the left hand end of the slide valve 8 as viewed in Fig. 1 and has pressed the slide valve over to the right as viewed in said figure and holds it in position. The pilot valve was placed in this (up) position by the movement of the shift rod 31 as previously explained, and in moving to this position any water confined above the land 85 was forced into the duct 79 and through port 80 into the chamber 59 which, it will be remembered, communicates with the exhaust port. The main valve 8, in moving to the right (as viewed in Fig. 1) forces the water between its right hand end and its adjacent plug 48 through port 78 into duct 77, thence into the interior of chamber 70 between the lands 86 and 87, and thence through ports 90 into bore 88 of the pilot valve thence out through ports 89 at the top of the said valve and into ducts 79, through port 80 and therefrom to chamber 59 to the exhaust. Referring to Fig. 8 there is also a duct or bypass 81 associated with the chamber 70. The lower end of the bypass opens into the lower end of the chamber 70 as at 82, and the upper end at a point 83 intermediate the length of the said chamber, said point 83 being above the land 85 of the pilot valve when the latter is at the lower limit of its movement (Fig. 8) but between the lands 85, 86 when the pilot valve is at the upper limit of its movement (Fig. 4). Part of the pressure water entering through duct 73 passes between lands 85 and 86 and through the bypass 81 from point 83 to the lower end of chamber 70 at point 82 beneath pilot

valve 10. The pilot valve 10 is therefore held in its upper position by water exerting inlet pressure on the lower end of said valve this pressure more than counteracting the exhaust pressure now being applied to the upper end of said valve by the exhaust water passing from below the piston 5. This gives substantial synchronism between main and pilot valve.

Referring now to Fig. 3, it is to be remembered that the position of the pilot valve shown in this figure corresponds with the position of the slide valve 8 as viewed in Fig. 2. In the position shown in these views, the piston 5 has reached the lower end of its stroke, has moved the shifting rod 31 downward and moved the pilot valve 10 to its lowermost position. Water beneath the pilot valve is pushed up through the bypass 81 into the space between lands 84 and 85 and through passages 79 and 80 into exhaust chamber 59. At this time water under inlet pressure from the chamber 57 has passed through port 74 into duct 73 and has entered the chamber 70 of pilot valve casing 9 between the lands 85 and 86 which now embrace between them the inner ends of both ducts 73 and 77. Water therefore entering the chamber 70 of casing 9 through duct 73 flows to duct 77 and through port 78 into the right hand end of main valve chamber 7, (as viewed in Fig. 2). Pressure has therefore been applied to the right end of the valve 8 (as viewed in Fig. 2) and has shifted it to the left and holds it in that position. In moving to the left (as viewed in Fig. 2) the valve 8 has pushed before it the water trapped between its left hand end and the adjacent plug 48 and has caused the trapped water to flow therefrom through port 76 into duct 75 and from duct 75 into the upper end of chamber 70 in casing 9 above land 85 whence it passes through duct 79 and port 80 into chamber 59 which, it will be remembered, is in direct communication with the exhaust port. At this time the upper end of the pilot valve is subject to inlet pressure in chamber 46.

The screw plugs 92 shown as closing the outer end of the several ducts 73, 75 and 77 are merely incidental to the method of manufacture of the casing because said ducts have been formed by drilling. The screw plugs 93 and the holes plugged by them are also merely incidents of the mode of manufacture.

It will be understood that, as this motor is intended particularly to utilize water as the motive fluid the metal of which the metallic parts are made should be non corrosive. The mechanism comprises few parts, is of extreme simplicity and devoid of springs, pivots, and compound transmission elements. The small number of fixed parts, their organization and arrangement con-

duces to compactness and strength. The retarding action of plates 37 and 38 in conjunction with ports 35 of stop plate 34, cooperating with the lost motion connection 6 between shifter rod 31 and pilot valve 10 and the frictional engagement of the latter in the cylinder produces silent and steady operation of the motor; while the direct connection between the inlet chamber 57 and 10 the lower end of chamber 70 substantially synchronizes the movements of valves 10 and 8.

Having thus fully described the invention, what is claimed and desired to secure by Letters Patent is:

1. In an expansible chamber motor, a combined motor support and valve casing provided with inner and outer seats having a common axis and separated in the direction 20 of said axis by an annular chamber within the casing, the outer seat being of greater diameter than the inner; a cylinder having one end secured to the inner seat, a cylindrical housing having one end secured to 25 the outer seat and its outer end extending beyond the outer end of the cylinder, thereby forming between the cylinder and housing an annular passage way in communication with said annular chamber and with 30 the interior of the cylinder at the outer end of the latter; a cap secured to the outer end of the cylindrical housing; a piston operating in the cylinder; a piston rod slidable through the cap; said combined support and 35 casing having a valve chamber provided with inlet and exhaust ports and suitable ports and passageways of communication with said annular chamber and the inner end of the cylinder; and a valve for controlling said ports.

2. In an expansible chamber motor, a cylinder, a piston therein, a valve casing having suitable ports and passageways for conducting fluid to or from opposite ends 45 of said cylinder, a valve in said casing for controlling said ports and passageways, a valve shifting rod adapted to be shifted by the movement of the piston at opposite ends of its stroke, stop means on the shifting rod 50 and stop means arranged to cooperate with said stop means on the shifting rod for limiting the endwise movement of the latter, and means whereby the movements of the valve shifting rod are rendered effective to shift said valve.

3. In an expansible chamber motor, a combined motor support and valve casing having a cylinder seat, a cylinder having one end secured to said seat, a piston operating 60 in said cylinder, a valve shifting rod within the cylinder adapted to be shifted by the piston at the opposite ends of its stroke, a guide for the lower end of said rod, a stop on said rod at each side of the guide for 65 limiting the longitudinal movement of the

rod, said combined support and casing having a valve chamber provided with inlet and exhaust ports, and suitable ports and passageways of communication with the opposite ends of said cylinder; a valve for controlling said ports, and means whereby the movements of the valve shifting rod are rendered effective to shift said valve. 70

4. In an expansible chamber motor, a cylinder, a piston therein, a valve casing 75 having a main valve chamber and suitable ports and passageways for conducting fluid to or from opposite ends of said cylinder, a pilot valve chamber, and control ports between said chambers; a valve in said main valve chamber, a pilot valve in said pilot valve chamber, valve shifting means connected to said pilot valve and adapted to be operated by the piston at opposite ends of its stroke stops on said shifting means, and means cooperating with said stops for limiting the movement of said shifting means and preventing impact of the pilot valve with its casing at opposite ends of its stroke. 80

5. In a water motor having a cylinder, a reciprocating piston, a main valve and a reciprocating pilot valve; in combination, elastic means for retaining the pilot valves at the opposite extremes of its stroke, a valve shifting rod adapted to operate the pilot valve, means whereby the shifting rod will be engaged by the piston as the latter approaches the opposite extremes of its stroke and means within the cylinder adapted to cushion the stroke of the shifting rod, limit its stroke and eliminate noise comprising a spider bridging the cylinder having a guide passage for the shifting rod and plates carried by the shifting rod on opposite sides of the spider, adapted to partially close the cylinder in association with the spider as the shifting rod approaches the opposite ends of its stroke. 95

6. In an expansible chamber motor, a cylinder, a piston therein, a valve casing having a main valve chamber and a pilot valve chamber, a chamber disposed between the inner end of the cylinder and said pilot valve chamber, inlet and exhaust ports, suitable ports and passageways of communication with the opposite ends of said cylinder, and control ports between said valve chambers; a valve in the main valve chamber, a pilot valve in the pilot valve chamber, one end of said pilot valve extending into said chamber that is disposed between the inner end of the cylinder and the pilot valve chamber, a valve shifting rod within said cylinder adapted to be shifted by the piston at each end of its stroke, and a finger secured to said shifting rod and having a loose connection with said pilot valve. 100

7. In an expansible chamber motor, a cylinder, a piston therein, a valve casing 105

having a main valve chamber and a pilot valve chamber, a chamber disposed between the inner end of the cylinder and said pilot valve chamber, inlet and exhaust ports, suitable ports and passageways of communication with the opposite ends of said cylinder, and control ports between said main valve and pilot valve chambers; a valve in the main valve chamber, a pilot valve in the pilot valve chamber, the neck of said pilot valve having an annular groove and extending into said chamber that is disposed between the inner end of the cylinder and the pilot valve chamber, a valve shifting rod within said cylinder adapted to be shifted by the piston at each end of its stroke, and a finger secured to said shifting rod, said finger having a notched portion engaging said groove.

20 8. In an expansible chamber motor, a cylinder, a piston therein, a valve casing having suitable ports and passageways for

conducting fluid to or from opposite ends of said cylinder, a pilot valve and a main valve in said casing for controlling said ports and passageways, a pilot valve shifting rod adapted to be shifted by the movements of the piston at opposite ends of its stroke a combined stop and guide plate having fluid passages therein through which motive fluid passes to and from one end of said cylinder, said shifting rod being guided by said plate, spaced stop and throttling members on said shifting rod at opposite sides of said plate, said members being constructed and arranged to partially close the passages in said plate at each end of the stroke of said shifting rod.

In testimony whereof I affix my signature.

TERESA CATHERINE ADAMS,
Administratrix of Frank A. Adams,
Deceased.
